UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S DRESS.

SPECIFICATION forming part of Design No. 14,827, dated February 26, 1884.

Application filed January 23, 1884. Term of patent 3½ years.

To all whom it may concern:

Be it known that I, SARAH JANE SHIELS, of the city, county, and State of New York, have invented and produced a new and original Design for a Pattern of a Lady's Dress, (numbered 9,075;) and I do hereby declare that the engraved prints accompanying this specification convey to any one accustomed to using paper patterns a clear understanding of how a garment made up by the pattern will appear.

The design shows ample fronts closing all the way down, and displaying a deep cluster of short rows of shirrings at the neck, and another similar cluster at the waist-line; an ample back,

also exhibiting a deep cluster of shirrings crossing its full width at the neck, and another similar cluster at the waist-line; a standing collar, and full-length sleeves having a shirring at the wrist of each.

What I claim as my invention, and desire to secure by Letters Patent, is—

The design for a lady's dress, as shown in the engraved prints accompanying this specification.

SARAH JANE SHIELS.
